[57] CLAIM

The ornamental design for can opener, as shown and described.

DESCRIPTION

FIG. 1 is a perspective view as seen from the top, front, and left side of a first embodiment of a can opener showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a perspective view as seen from the top, front, and left side of a second embodiment of a can opener showing our new design;

FIG. 9 is a left side elevational view thereof;

FIG. 10 is a front elevational view thereof;

FIG. 11 is a right side elevational view thereof;

FIG. 12 is a rear elevational view thereof;

FIG. 13 is a top plan view thereof; and,

FIG. 14 is a bottom plan view thereof.

The broken lines in FIGS. 1 through 5 and 7 showing the power cord and feet are used for illustrative purposes only and form no part of the claimed design.

The broken lines in FIGS. 8 through 14 showing the power cord, feet, rear vents, a honing stone aperture, and the power cord aperture/lock are used for illustrative purposes only and form no part of the claimed design.
